UNITED STATES PATENT OFFICE

165,310

MOTION-PICTURE PROJECTOR

Glenn W. Tamm, Park Ridge, Ill., assignor to
Ampro Corporation, Chicago, Ill., a corpora-
tion of Illinois

Application July 31, 1951, Serial No. 16,097

Term of patent 14 years

(Cl. D61—1)

To all whom it may concern:

Be it known, that I, Glenn W. Tamm, a citizen of the United States, residing at Park Ridge, State of Illinois, have invented a new, original, and ornamental Design for Motion Picture Projector, of which the following is a specification, reference being had to the accompanying drawing, forming a part hereof.

Fig. 1 is a side elevation of the operator's side of the projector.

Fig. 2 is a side elevation of the opposite side.

Fig. 3 is a front elevation.

Fig. 4 is a top plan.

Fig. 5 is a rear elevation.

I claim:

The ornamental design for a motion picture projector, as shown.

GLENN W. TAMMEN.
